UNITED STATES PATENT OFFICE.

KARL KIEFER, OF CINCINNATI, OHIO.

FILLING APPARATUS.

1,181,391.

Specification of Letters Patent.

Patented May 2, 1916.

Application filed December 18, 1909. Serial No. 533,934.

To all whom it may concern:

Be it known that I, KARL KIEFER, a citizen of the United States, residing at Cincinnati, in the county of Hamilton and **5** State of Ohio, have invented certain new and useful Improvements in Filling Apparatus, of which the following is a specification.

My invention relates to filling machines, **10** and has for its object the provision of means to increase the accuracy of filling, convenience of operation, and efficiency and durability of the apparatus as a whole.

My invention consists in the parts and in **15** the details of construction and arrangement of parts, as will hereinafter be more fully described and claimed.

In the drawings: Figure 1 is a view, partly in elevation and partly in vertical **20** section, of my improved filling apparatus. Fig. 2 is a detail perspective view of one of the universal hangings for the filling tubes. Fig. 3 is a similar detail of the fork forming part of one of these hangings. Fig. 4 is **25** a detail of one of my improved filling tubes, shown with the sleeve raised, and with part of the structure shown in vertical section. Fig. 5 is a side elevation of the device, with the sleeve lowered, and the tube closed.

30 The filling tubes are carried by the ring A, and are of a type similar to those illustrated in my Patent No. 865,395, of September 10, 1907.

The machine operates by siphonal action, **35** the liquid supply being under atmospheric pressure, and the air being allowed to escape from the bottle between the bottle-top and the stop on the tube, which fits inaccurately against the bottle-top, without a gasket. **40** The flow of liquid into the bottle is stopped when the liquid in the bottle reaches the level of the liquid supply. A valve in the end of the tube closes as the tube is withdrawn from the bottle, keeping the tube and **45** its supply passage filled with liquid. Thus, in starting the machine, it is necessary to fill the tube and passage, by suction, or otherwise as will hereinafter be explained; but after that, the flow will start as soon as **50** the valve in the end of the tube is opened, at each application of a bottle, due to the siphonal action.

The machine as a whole is mounted on a base B, by means of a column C, rigidly **55** secured to the base. A hollow column D sur-

rounds this stationary column C, and is rotatable thereon. The upper end of this hollow column supports a tank E, which is made with a bottom e having a hub e¹ fitting rigidly in the open upper end of the **60** hollow column.

The tank, for sanitation, and for ready inspection of its interior, has a shell e² of glass, mounted on the bottom and secured thereto, with suitable gaskets, by an upper **65** rim e³ with bolts e⁴ engaging the bottom, outside the shell.

The hub e¹ of the bottom e of the tank E is open, and a central tube e⁵ is rigidly secured therein, rising therefrom to about the **70** height of the upper side of the rim of the shell, this tube forming a liquid-tight passage up through the center of the tank for the reduced part c of the central stationary column C to extend up through. The cover **75** F for the tank is secured to this reduced extension c, at the upper end thereof. This cover F extends out over the rim of the shell, and lies closely adjacent to said rim, and to the upper end of the central tube, so **80** as to close the tank against the outer air in as thorough a manner as is necessary.

As above stated, according to the principle of the machine, the liquid in the tank must be open to atmospheric pressure, to **85** cause the siphonal action. It is, however, generally undesirable to have the surface of the liquid freely exposed to the air in such manner as to allow considerable evaporation. This is especially important when **90** filling alcoholic liquors or any volatile fluids. Therefore, while an air-tight connection between the cover and the top of the tube and rim of the shell is not permissible, nor even desirable, a close approach of these **95** parts, such as will prevent appreciable currents of air over the surface of the liquid, is of advantage. The relative movement between the parts is also freely permitted, and there is no wear at these points, as would be **100** the case were it necessary to have gasket connections between them. It will thus be apparent that this construction is especially suited to a machine operating on the principle hereinbefore set forth. This cover, thus mounted stationarily, while the tank itself is rotatable, carries the inlet I with the valve V, which has its float apparatus F' depending from it, within the tank; the buoyant member f of the float apparatus, which **105** **110**

may be of cork, embraces the central tube e^5 and the reduced part e of the column C therein.

By the construction just described, the tank is allowed to revolve, with the ring A that carries the filling tubes, while the valve, controlling the supply of liquid to the tank, and the float mechanism, regulating the valve, are allowed to remain stationary, with the source of supply of liquid, while at the same time, any complicated revolving connection, from source of supply to filling tubes, is avoided.

The ring A that carries the filling tubes, before mentioned, is supported by the upper standard G, which comprises radial posts 2 curving upward from a hub which slides up or down on the hollow column D, being raised or lowered by means of a handwheel 3 running on threads on the exterior of the hollow column. This standard is held to rotate with the hollow column, at any adjustment, by a key g sliding in a keyway d in the column D.

The machine may have any convenient number of filling tubes arranged around the ring A, only two being shown, and the positions of others being merely indicated by vertical broken lines, for sake of clearness. Lower on the hollow column D, the lower standard H is mounted, having radial arms 4 curving upward from a hub that surrounds the column. A handwheel 3', similar to the handwheel 3, runs on threads on the hollow column, to adjust the lower standard up or down. This lower standard is also prevented from turning on said column, but held to revolve with it, by a key h sliding in the keyway d in the column. The arms 4 carry the table K, on which rest the vessels 5, to be filled. Adjustment of the table K vertically allows for filling bottles of various heights. The ring A, with the filling tubes carried thereon, is adjusted vertically, as above described, to allow the extent of projection of a filling tube into a bottle to be regulated, and to allow the distance of the outlet of any given tube below the level in the tank E to be regulated. Thus, with a small bottle, not only is it desirable to use a smaller filling tube, but the projection of even such a tube below said liquid level may be in bulk equal to a considerable proportion of the capacity of the bottle, whereupon this bulk must be lessened by raising the tube with respect to the liquid level. With a larger bottle, where the bulk of the tube is not so significant, the tube not only may be larger, but may be lowered, so that the advantage of rapid outflow resulting from increasing the distance of the outlet below the liquid level in the tank E, is attained. Thus, by having the tubes as well as the table vertically adjustable with respect to the tank E and with respect to each other,

every bottle, of any size, may be filled under the conditions best suited to it. Also, it is customary to furnish machines of this kind with interchangeable stems of different diameters and different lengths, to provide for filling bottles of different sizes, as above alluded to. These adjustments, of course, allow the conditions to be regulated for the use of these various tubes, as well as for accommodating the various bottles to be filled by the tubes.

Radial ribs 6 on the table divide it into compartments corresponding with the filling tubes, and the vessels, engaging the ribs when pushed sidewise, serve to rotate the table, and with it the hollow column D and the ring A, carried thereby, with the filling tubes, as well as the tank E, as above described.

In taking the bottles off the filling tubes, careless operators are liable to bend the tubes, so that some form of swivel in the hanging of the tube is required. Some machines are provided with radially swinging tubes, but to render the machine thoroughly proof against such damage, a universal hanging is required. I meet this requirement with a simple, substantial and quickly separable universal hanging bearing 7, for each of the filling tubes 8, bolted rigidly on the ring A, before described. A fork 9, embracing and pivoted to each tube, has a stem 9' provided with a transverse slot 10, near its free end, and having an inclined face 12 on this end. The bearing 7 has a barrel 11, with a transverse slot 11' cutting into its interior, near the rear end thereof. A spring 11'' is secured to the bearing 7, with an arm lying within the slot 11', and when the stem 9' of the fork 9 is pushed into the barrel, the inclined face 12 raises the arm of the spring. Then, when the slot 10 in the stem registers with the slot 11' in the barrel, said arm of the spring will snap into the slot in the stem.

The slot in the stem is of sufficient depth to allow the proper swiveling movement of the fork in the bearing without the spring becoming disengaged from the stem. Thus the fork is retained against unintentional displacement from the bearing, after insertion. For removal, the spring arm continues past the slot in the barrel, to be engaged by the finger and raised out of the slot in the stem. This combination is best illustrated in Fig. 2. This quickly separable hanging is especially convenient in starting the machine, as it is only necessary to lower the bottle, together with the filling tube on its separated part of the hanging, with the tube open, below the level of the liquid in the tank E, whereupon the liquid flows by force of gravity, avoiding necessity of suction, as has heretofore been necessary. As soon as the liquid starts to flow, the tube is

hung in place, in the convenient manner above described.

The filling tube usually consists, as in my former patent, above mentioned, of the tube 13, proper, and a sleeve 14, around it, the tube having a lateral orifice near its end, over which the sleeve slides. The sleeve, in practice has considerable clearance on the tube, making it necessary to close the annular space between them. This has been done by means of an annular valve seat, either of metal or of rubber. If of rubber, the sleeve cuts the seat, after a short period of use. If of metal, the deflection of the tube, or of the sleeve on the tube, unavoidable in practice, allows vaciation of the contact of the sleeve and the seat. In either case, leakage results. To compensate for this, I employ a combination of metal and rubber, the seat 17 being of metal, not subject to cutting by the sleeve 14, and adapted to remain true therewith if allowed to be deflected with the sleeve, and the rubber washer 15 supporting the seat 17 and allowing such deflection.

It is necessary that the washer 15, which is held in place by a nut 16, be of ample cross section, to afford a stable support for the seat, and to be durable enough to be practical. On the other hand, the seat must not project appreciably past the diameter of the sleeve at any point, since the filling tube, as a whole, must be capable of insertion into bottle-necks of small caliber. I provide the flexible support, in combination with the tube and sleeve, and fulfil the above conditions, by providing the end of the tube 13, proper, with a solid end, having a reduced part 18, so that the valve seat 17, surrounding this reduced part 18, may undercut the tube 13, and may have the washer 15 of the required cross section, and with the required bearing area between the under side of the seat and the upper side of the washer, without objectionable extension in diameter at the end of the filling tube. The extremity of the reduced part 18 receives the nut 16, which holds the washer and seat in place, as before alluded to.

As shown in the drawing, the valve seat lies in a plane parallel with the end of the sleeve, and makes contact with the end of the sleeve somewhat above the undercutting part of the tube proper, but it will be understood that the seat may have a conical or spherical surface, with the lower end of the sleeve accordingly shaped, as preferred, and as is well known in the art. The seat 17 should, preferably, fit somewhat loosely around the reduced part 18 of the end of the tube proper, permitting ample deflection of the seat with the sleeve, as has been mentioned. The total proportions of the rubber washer 15, required by the construction shown, have determined, as in this drawing,

to be ample, but at the same time results in increased durability of the valve.

Having described my invention, what I claim as new and desire to secure by Letters Patent is:

1. In filling apparatus, a revolving column, a liquid tank carried by the revolving column, filling tubes having liquid outlets and communicating with said tank, and vessel-carrying means to hold vessels for insertion of the tubes, said tubes and said vessel-carrying means being supported on said revolving column to revolve with said tank but to be adjusted with respect to each other and with respect to said tank. 70

2. In filling apparatus, in combination with a filling tube thereof, a universal hanging for the tube comprising a bracket, and a fork turning in the bracket and embracing and having pivotal connection with the filling tube, at an angle to the turning of the fork in the bracket. 75

3. In filling apparatus, in combination with a filling tube thereof, a universal hanging for the tube comprising a bracket having a barrel, a fork having a stem entering the barrel of the bracket, said fork embracing and having pivotal connection with the filling tube at an angle to the stem, said barrel of the bracket having a slot cutting into 95 its interior, said stem of the fork having a slot to meet the slot in the barrel, and a detent on said bracket having a part entering the slot in the stem through the slot in the barrel and having engaging means to remove it from the slot in the stem, said stem having an inclination to engage the part of the detent on insertion of the stem into the barrel. 100

4. In filling apparatus, a filling tube comprising a slidable sleeve, an annular valve seat to engage the sleeve, and a flexible washer supporting said valve seat, said washer and the part of the seat which it engages being of materially greater area than 105 the parts of the sleeve and valve seat that engage together, and said seat and washer being of outside diameter not greater than that of said sleeve. 110

5. In filling apparatus, a sleeve, a member inside the sleeve closing its end loosely, and slidably therein, an annular valve seat engaging the end of the sleeve to tightly close the end of sleeve, said valve seat surrounding and undercutting said member 115 that is inside the sleeve, and a flexible supporting member surrounding said inside member and substantially coextensive with the engaging part of said undercutting valve seat. 120

6. In filling apparatus, a filling tube with closed end and lateral orifice, a sleeve around the tube sliding over the orifice, an annular valve seat surrounding the closed end of the tube to engage with the end of the sleeve, 125 130

said closed end of the tube having a reduced part and said valve seat undercutting the closed end of the tube at said reduced part, and a flexible supporting member for the 5 valve seat surrounding said reduced part, substantially coextensive with the engaging part of said undercutting valve seat.

In testimony whereof I have signed my

name to this specification in the presence of two subscribing witnesses, this 16th day of 10 December, 1909.

KARL KIEFER.
